COMBINATION AIR FILTERING AND COLLECTING UNIT FOR TEXTILE WASTE PRODUCTS

R. Hovan Hocutt and Thomas E. Mullinax, Charlotte, N.C., assignors to Pneumafil Corporation, Charlotte, N.C., a corporation of Delaware

Design application Aug. 27, 1965, Ser. No. 87,198, now Patent No. 205,760, dated Sept. 20, 1966, which is a division of design application Ser. No. 78,632, Feb. 14, 1964, now Patent No. 203,155, dated Dec. 14, 1965. Divided and this application July 27, 1966, Ser. No. 3,233

Term of patent 7 years

(Cl. D9—2)

FIG. 1.

FIG. 2.

FIG. 1 is a front perspective view of a combination air filtering and collecting unit for textile waste products embodying our new design;

FIG. 2 is a rear perspective view thereof.

This application is a division of my co-pending application Ser. No. 87,198, filed Aug. 27, 1965, now Patent D.205,760, granted Sept. 20, 1966, which was a division of my application Ser. No. 78,632, filed Feb. 14, 1964, now Patent D.203,155, granted Dec. 14, 1965.

What we claim is:

The ornamental design for a combination air filtering and collecting unit for textile waste products, as shown.
